[57] CLAIM

The ornamental design for a belt mounted massaging unit, as shown and described.

DESCRIPTION

FIG. 1 is a perspective view of a belt mounted massaging unit embodying my new design.

FIG. 2 is a bottom plan view of one of the two identical pads forming a part of the device.

FIG. 3 is a side elevational view showing the longer dimension of the pad.

FIG. 4 is an elevational view from the side opposite that shown in FIG. 3.

FIG. 5 is a top plan view of the pad.

FIG. 6 is a side elevational view of the pad showing the shorter dimension thereof.

FIG. 7 is an elevational view from the side opposite that shown in FIG. 6.

FIG. 8 is a front elevational view of a base unit forming a part of the device.

FIG. 9 is a side elevational view of the base unit, the other side being identical except that it does not have an aperture for wires to come out of it.

FIG. 10 is a back elevational view of the base unit.

FIG. 11 is a top plan view of the base unit.

FIG. 12 is a bottom plan view of the base unit.
